DESIGN FOR A HANDBAG FRAME

Nelson Liebes, New York, N. Y.

Application December 3, 1940, Serial No. 97,040

Term of patent 3½ years

To all whom it may concern:

Be it known that I, Nelson Liebes, a citizen of the United States of America, residing in city of New York, county of New York, and State of New York, have invented a new, original, and ornamental Design for a Handbag Frame, of which the following is a specification, reference being had to the accompanying drawing, forming part thereof.

Fig. 1 is a front perspective view of a handbag frame showing my new design.

Fig. 2 is a rear perspective view illustrating the lock in open position.

I claim:

The ornamental design for a handbag frame, as shown.

NELSON LIEBES.
